PACK FOR FRAGILE ARTICLES

Walter H. Randall, Waterville, Maine, assignor,
by mesne assignments, to The Canal National
Bank of Portland, Portland, Maine, a national
banking association of the United States, and
William B. Nulty, Portland, Maine, as trustees

Application April 22, 1950, Serial No. 9,422

Term of patent 14 years

(Cl. D58—13)

To all whom it may concern:

Be it known that I, Walter H. Randall, a citizen of the United States, residing at Waterville, county of Kennebec, State of Maine, have invented a new, original, and ornamental Design for Pack for Fragile Articles, of which the following is a specification, reference being had to the accompanying drawing, forming part hereof.

This application is a continuation-in-part of my application Serial No. D. 141,402 filed September 15, 1947, and now pending.

In the drawing:

Fig. 1 is a perspective view of a pack for fragile articles, showing my new design, the pack being open.

Fig. 2 is an end elevation of the pack, as seen when closed.

Fig. 3 is a front elevation of the closed pack.

Fig. 4 is a top plan view of the pack.

The characteristic features of my design reside

in the portions shown in full lines in the drawing.

I claim:

The ornamental design for a pack for fragile articles, as shown and described.

WALTER H. RANDALL.
